Inventor,

UNITED STATES PATENT OFFICE.

CLINTON H. CALDWELL, OF JOHNSONBURG, PENNSYLVANIA.

RAIL-JOINT.

1,171,701.

Specification of Letters Patent. Patented Feb. 15, 1916.

Application filed November 6, 1915. Serial No. 60,103.

To all whom it may concern:

Be it known that I, CLINTON H. CALDWELL, a citizen of the United States, residing at Johnsonburg, in the county of Elk and State 5 of Pennsylvania, have invented a new and useful Rail-Joint, of which the following is a specification.

This invention relates to rail joints, one of its objects being to provide a simple, compact and durable joint which is cheap to manufacture and which permits the necessary expansion and contraction of the rails without danger of the parts becoming accidentally separated, the various portions of 15 the joint being held together without the use of nuts as heretofore employed.

A further object is to provide a rail joint the parts of which can be readily disconnected whenever it is desired to repair or 20 replace the same.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings: Figure 1 is an elevation of one side of the rail joint. Fig. 2 is an elevation showing the opposite side of the joint. Fig. 3 is a section on line A—B, Fig. 1. Fig. 4 is a section on line C—D, Fig. 2. Fig. 5 is a detail view of one of the fastening bolts. Fig. 6 is a detail view of a 40 key.

Referring to the figures by characters of reference R designates rails of the usual form, these rails being provided with bolt receiving slots r as ordinarily.

45 The rail joint constituting the present invention includes a chair 1 and opposed fish plates 2 and 2', these fish plates being provided with slots 3 designed to register with the slots r. The fish plate 2 is integral with 50 the chair while fish plate 2' is separate and rests upon the chair 1 and back of a rib 1^a on the chair. The bolts used in connection with the rails and fish plates each includes a cylindrical stem 4 provided at one end with 55 a head 5 having opposed flat sides so that the thickness of the head is substantially the

same as the diameter of the stem 4. The length of the head is somewhat less than the length of each of the slots r and 3. Each stem 4 is provided at that end remote from head 5 with an angular enlargement 6 having a central rib 7 on its inner face for engagement in a slot 8 in a key 9. This key is in the form of a tapered plate having a slot 8 near each end and an intermediate slot 10 60 adapted to engage a stud 11 on the rail. The distance between the enlargement 6 and the head 5 is substantially equal to the distance between the outer faces of the fish plates 1 and 2 when said fish plates are 65 assembled upon opposed sides of the rails R.

In using the parts herein described the fish plates are placed in proper positions upon the sides of the rails after which the bolts are inserted successively through the 75 alining series of apertures. In placing each bolt in position its head 5 is turned so as to extend longitudinally of the slots after which said head is thrust through the slots and the bolt given a one-quarter turn so as 80 to bring the head transversely across the slot in the fish plate engaged by the head and the ribs 7 to vertical positions. In the drawings the heads are shown extended transversely of the slots in the fish plate 2'. 85 With the bolts thus positioned they cannot, obviously, be withdrawn from the slots. Furthermore the enlargements 6 on the bolts limit the movement of the bolt through the slot. When each bolt is given a one quarter turn as described, the head 5 of the bolt will 90 engage the outer face of the fish plate 2' while the rib 7 will engage the outer face of the fish plate 2. After the various bolts have been positioned as described, the keys 95 are placed against the fish plate 2, so as to receive the ribs 7 in slots 8 and the studs 11 in slots 10.

It will be apparent that bolts constructed and assembled as described will constitute 100 efficient connections between the rails and fish plates and will not prevent the necessary expansion and contraction of the rails.

It will be noted by referring particularly to Fig. 1 that one key 9 is provided for each rail R. Consequently by removing one of these keys one of the rails can be removed from the fish plates without disconnecting the fish plates from the other rail, as would be necessary should a single key be combined 105 with the bolts of both rails.

It will be noted that the stem of each bolt

is of uniform diameter so that it is of uniform strength and it will be noted furthermore that the entire bolt can be readily produced without any machine work. The joint can be combined with standard rails and fish plates and, while the joint allows for expansion and contraction of the rails, the base portions of the fish plates are held tightly clamped by the bolts upon the base flanges of the rails so that the rails are at all times tied properly together at their bases.

What is claimed is:

1. The combination with abutting rails and opposed fish plates fitted against the sides of the rails, said rails and fish plates having alining slots, of bolts insertible into the alining slots, each bolt having a flat head insertible through the slots and adapted to engage the outer face of one of the fish plates when the bolt is given a one quarter turn, an angular enlargement upon that end of each bolt remote from the head and provided with a rib, a key having slots for the reception of the ribs on the bolts thereby to hold the bolts against rotation.

Copies of this patent may be obtained for five cents each, by addressing the "Commissioner of Patents, Washington, D. C."

and with the heads in engagement with the fish plates adjacent thereto, and means upon the rails for detachably engaging the keys.

2. The combination with abutting rails and fish plates engaging the sides thereof, said rails and fish plates having alining slots, of bolts insertible through the slots, each bolt including a flat head insertible through the slots and adapted to engage the outer side of one of the fish plates when the bolt is given a one quarter turn, an enlargement upon that end of each bolt remote from the head and having a rib and separate keys having slots for the reception of the ribs upon the bolts engaging the respective rails, and means engaging the keys and extending from the rails for holding the keys against removal from the rails.

In testimony that I claim the foregoing as my own, I have hereto affixed my signature in the presence of two witnesses.

CLINTON H. CALDWELL.
